CLAIM

The ornamental design for a rear projection television receiver, as shown and described.

DESCRIPTION

FIG. 1 is a perspective view of the front, left and top of a rear projection television receiver showing our new design.

FIG. 2 is a front view of the design according to the invention.

FIG. 3 is a left side view of the design according to the invention.

FIG. 4 is a right side view of the design according to the invention.

FIG. 5 is a top plan view of the design according to the invention.

FIG. 6 is a bottom view of the design according to the invention.

FIG. 7 is a rear view of the design according to the invention.

FIG. 8 is a partially enlarged perspective view at A shown in FIG. 2 thereof; and,

FIG. 9 is a partially enlarged perspective view at B shown in FIG. 2 thereof.
